KEY CONTAINER

Carl G. Smith, Wichita, Kans.

Application December 14, 1946, Serial No. 716,405

5 Claims. (Cl. 150—40)

1

This invention relates to new and useful improvements in a key container, and has particular reference to a key container wherein keys are retained on a post within a flexible cover.

The principal object of the present invention is the provision of a key container comprising a single piece of flexible leather, or similar material, folded over to form a hollow container, a mounting post extending between opposite sides of said container on which a number of keys may be carried, said post being slidably movable away from one side of said container to permit insertion and removal of keys, and spring means urging said mounting post toward the closed position.

Another object is the provision of a means whereby said mounting post may be releasably locked in the open position against the pressure of the spring, thereby facilitating the removal and insertion of keys.

A further object is the provision of a means whereby said key container may be attached to a key ring, key chain, or other carrying device.

Further objects are simplicity, economy, and ruggedness of construction, and ease and dependability of operation.

With these objects in view, as well as further objects which will become apparent during the course of the specification, reference will be had to the drawing, wherein:

Figure 1 is a front view of a key container embodying the present invention, said container being shown attached to a key chain.

Fig. 2 is an enlarged sectional view taken on line II—II of Figure 1.

Fig. 3 is a fragmentary vertical section taken on line III—III of Figure 2.

Fig. 4 is a view similar to that shown in Figure 3, with the slidable mounting post in the retracted position.

Fig. 5 is a fragmentary vertical section taken on line V—V of Figure 3.

Fig. 6 is an outside view of the flexible container opened to a flat position.

Like reference numerals apply to similar parts throughout the several views, and the numeral 10 applies to a cover consisting of a single piece of leather or other flexible material cut substantially to the shape shown in Figure 6, and adapted to be folded as shown in Figure 1 to form a substantially tubular container open at top and bottom and wider at the top than at the bottom. Cooperating snap fastener members 12 and 14 fixed in opposite edges of cover 10 serve to retain said cover in the folded or closed position. An

2

eyelet 16 is fixed in the lower edge of cover 10, and a ring 18 is passed through said eyelet. Said ring may be attached to a key chain 20, a key ring, or other similar device. The container may, of course, also be carried without attaching it to any ring or chain.

A U-shaped frame member 22 having substantial rigidity extends partially around the inside of said container adjacent the upper edge 10 thereof. The forward leg of said frame member is rigidly attached to cover 10 by a pin 24 having an enlarged head 26, said pin extending inwardly through cover 10 and frame 22, and being slightly upset at its inner end to retain it rigidly in position. The inward end of said pin is extended inwardly to form a positioning pin 28.

The rearward leg of frame 22 is shaped to provide an outwardly extending bearing tube 30 in axial alignment with pin 24. Said tube extends 20 outwardly through hole 32 of cover 10, through a clamp washer 34, and is upset at its outer end to clamp said cover rigidly between said frame and said clamp washer.

A tubular mounting post 36 is slidably carried 25 in bearing tube 30, and normally extends through the container. Its inner end is equipped with a plug 38 having a socket 40 adapted to engage positioning pin 28, and its outer end is shaped to form a wide, flat head 42. Said mounting post 30 is urged inwardly to engage positioning pin 28 by helical spring 44 contained within the said 35 mounting post. Said spring abuts at its forward end against plug 38 and at its rearward end against disc 46 carried within said tubular mounting post. Said disc is maintained stationary with respect to frame 22 by means of a narrow flap cut from frame 22 adjacent mounting post 36 to form a detent 48, said detent being bent to project into said mounting post through a slot 40 50 cut longitudinally in the side of the said mounting post, as shown in Figures 3, 4 and 5. Said slot is provided at its forward end with a laterally offset portion 52.

To insert or remove keys, head 42 of mounting 45 post 36 is manually pulled rearwardly, compressing spring 44, until detent 48 abuts against the forward end of slot 50. Post 36 is then turned through a partial revolution to bring offset portion 52 of said slot into alignment with detent 50 48, thus securing said mounting post in the retracted position against the pressure of spring 44. The retraction of said mounting post opens a gap 54 between the inward end of said mounting post and positioning pin 28. Through this gap keys 56 may be placed on or removed from

the mounting post, said mounting post passing through holes 58 normally provided in the handles of said keys for mounting purposes. The mounting post is then rotated slightly to bring slot 50 into alignment with detent 48, whereupon spring 44 will move said mounting post inwardly into engagement with positioning pin 28, closing gap 54 and securing the keys on said mounting post. Positioning pin 28 serves as a support for the inward end of said mounting post.

The improvements I claim as new and desire to protect by Letters Patent are:

1. A key container comprising a single piece of flexible material folded to form a substantially tubular cover adapted to be opened along a longitudinal edge thereof, a flat rigid U-shaped frame member extending partially around the inside of said cover adjacent one end thereof and firmly fixed thereto, a mounting post slidably carried in one leg of said U-shaped frame member and extending outwardly through the wall of said cover, said mounting post normally extending through said cover and abutting against the opposite leg of said U-shaped frame member, means for slidably retracting said mounting post from engagement from said opposite frame leg whereby keys may be mounted on said mounting post, and means constantly urging said slidably mounting post inwardly toward its abutting position.

2. In a key container of the class described having a substantially tubular cover, means providing rigidly spaced apart front and rear walls, a tubular mounting post slidably carried in said rear wall and having its forward end closed and a longitudinal slot formed in the side thereof, a detent rigidly fixed to said rear wall and extending into said tubular mounting post through said slot, a spring carried within said mounting post, said spring bearing at its forward end against the closed forward end of said mounting post and at its rearward end against said detent, thereby urging said mounting post inwardly to bear at its forward end against said front wall, and means associated with the extended rearward end of said mounting post whereby said mounting post may be pulled rearwardly against the pressure of said spring.

3. In a key container having a substantially tubular cover of a flexible material, a flat, rigid frame member rigidly fixed to and extending partially around the inside of said cover adjacent one end thereof to present spaced apart forward and rearward legs, said frame member holding the front and rear walls of said cover in rigidly spaced apart relationship, a tubular mounting post slidably carried in the rearward leg of said frame member and extending forwardly to abut normally against the forward leg of said frame member, said mounting post being closed at its forward end and having a longitudinal slot in the side thereof, said slot having a laterally offset portion at the forward end thereof, a detent rigidly fixed to the rearward leg of said frame member and extending into said mounting post through said slot, a spring carried within said mounting post, said spring being compressed between said detent and the closed forward end of said mounting post, thereby urging said mounting post forwardly, a head rigidly fixed to the rearwardly extended end of said mounting post whereby said mounting post may be rearwardly retracted, said mounting post being rotatable when in the retracted position to move the

offset portion of said slot into alignment with said detent, thereby securing said mounting post in its retracted position.

4. A key container comprising a substantially tubular cover, means providing rigidly spaced apart front and rear walls, a mounting post slidably carried in said rear wall and extending inwardly through said cover to bear normally against said front wall, said mounting post having a socket formed in the forward end thereof, a positioning pin rigidly attached to and extending inwardly from said front wall in axial alignment with said mounting post, said pin being adapted to be engaged in said socket, and a spring means urging said mounting post into engagement with said positioning pin.

5. A key container comprising a single piece of flexible material folded to form a substantially tubular cover; cooperating snap fasteners releasably securing said cover in the closed position; a rigid U-shaped frame member firmly fixed to and extending partially around the inside of said cover adjacent one end thereof, whereby the front and rear walls of said cover are maintained rigidly in a spaced apart relationship; a tubular mounting post slidably carried in the rearward leg of said frame member and extending rearwardly through said rear wall and forwardly through said cover to abut normally against the forward leg of said frame member, said mounting post having a closed forward end with a socket formed therein, and a longitudinal slot formed in the side thereof, said slot having a laterally offset portion at the forward end thereof; a detent rigidly attached to the rearward leg of said frame member and extending into said tubular mounting post through said slot; a spring carried within said mounting post and compressed between said detent and the closed forward end of said mounting post, whereby said mounting post is urged against the forward leg of said frame member; a positioning pin rigidly attached to and extending inwardly from the forward leg of said frame member in axial alignment with said mounting post, said pin normally being engaged in the socket of said mounting post; and a flat head formed integrally with the extended rearward end of said mounting post, whereby said mounting post may be manually retracted to the rear compressing said spring, said mounting post being rotatable when in said retracted position to move the offset portion of said slot into alignment with said detent, thereby securing said mounting post in the retracted position.
